UNITED STATES PATENT OFFICE

2,494,529

VACUUM RUPTURE OPERATED PUMP

Axel M. Wirtanen, Eveleth, Minn.

Application February 23, 1945, Serial No. 579,347

3 Claims. (Cl. 230—52)

1

This invention relates to improvements in a vacuum operated pump and to one particularly adapted for use in supplying air to live bait in confined bodies of water such as minnows in pails or other types of containers used by fishermen.

It is contemplated that the pump may also be used to advantage for other purposes than that at present under specific considerations so well known to the fishing sportsman.

One of the principal objects sought at this time is that of providing simple and practical means of utilizing the suction of the intake manifold of an internal combustion engine commonly used upon boats in the practice of fishing, to operate a pump to provide air to live bait, such as minnows or the like, necessarily confined in a relatively small container of water.

Another object is to provide such means as will assure a constant supply of air irrespective of the fluctuations of the vacuum producing means supplying the operating power of the pump.

Other objects and advantages of the invention will appear in the further description thereof.

Referring now to the accompanying drawing forming part of this application, and in which, like reference numerals indicate like parts:

Fig. 1 is a certain vertical sectional view of the preferred type of pump showing its relation to cooperative parts in carrying into practice the invention, and

Fig. 2 is a diagrammatic lay-out illustrating the relative position of the various cooperating parts.

In the drawing, the numeral 1 represents a common outboard motor boat as used in hook-and-line fishing, and 2 is the motor, such being equipped, as is essential, with a carburetor, the latter having an air intake, commonly referred to as the intake manifold, for automatic supply of air to the engine fuel.

This manifold or intake is illustrated at 3, and is directly connected with the power receiving port 4 of the relatively small pancake-shaped pump casing 5.

The pump is preferably circular in form as viewed axially, but somewhat flattened upon opposite sides as at 6 and 7 with the latter being equipped with the diametrically-disposed holding clip 8 for slipping down against the inner wall of the bait receptacle, pail, or whatever the case may be.

The circumferential wall of the pump is preferably of outwardly extending, rather flat V-shape to provide an annular flat flange 9 extending wholly about the inner marginal rim of each half of the pump casing, thus forming an ideal flat surface for making a solid fixed union of the two parts as well as holding therebetween the similar annular flange or marginal edge 10 of the resilient diaphragm 11.

2

This diaphragm together with the smaller fixed division wall 12, divides the interior of the pump into three separate chambers: 13, 14, and 15, the largest one 13, by its alternate expansion and contraction, forming the power generating chamber.

The fluctuating capacity of the intermediate chamber 14 is, of course, in synchronism with that of chamber 13, and the chamber 14 is equipped with a simple flap or check valve 16 which controls outside air intake port 17 and will allow said chamber 14 to increase in capacity at each contraction of the power chamber 13 and thereby fill said chamber 14 with outside air through said port 17; then, when the reverse action or expansion of the chamber 13 occurs, the chamber 14 must discharge its contents, and, to accomplish which, the second simple flap-like discharge port and valve 18 is provided which feeds said forced air into the chamber 15.

This chamber 15 may aptly be referred to as the expansion chamber and has proved to function admirably as such when in operation in keeping a substantially uniform flow of air into the conductor tube 19 attached to the outlet port 20 from the chamber 15 leading into the water in the bait receptacle 21 in the boat 1, depending upon size of discharge.

The connection of the chamber 13 in the pump 5 with the intake manifold 3 of the motor 2 is accomplished by the tube 22.

The central portion of the diaphragm 11 is reinforced and made substantially rigid by means of the two metal discs 23 and 24 being clamped upon opposite sides thereof by the central bolt 25, the inner disc 24 also holding firmly in place one end coil of the two expansive helical springs 26 and 27. The opposite end of the larger spring 26 bears against and is practically the full size of the adjacent flat face of the pump and is designed to keep the chamber 13 in its fully expanded condition at all times.

The spring 27 is preferably conical in shape with its smaller end terminating in and carrying the flanged valve stem 28 which protrudes axially through the hole or port 29 formed in the center of the flat wall 6 of the pump 5, and it has been learned by experience that the capacity of this hole about the plug 28 must be some greater than that of the vacuum intake port 4 of the pump.

The stem 28 protrudes through and beyond the wall 6 of the pump, and the outermost end thereof is of bulb-like form for convenient reception of the vacuum cup-shaped rupture valve 30 which acts intermittently as a closure for the port 29, and the necessity of this cup-like shaped closure will appear later.

Thus, when the proper connections have been made as described and illustrated, intermediate the water in the bait receptacle and the intake manifold of the engine through the pump 5 and

the engine made to normally function, the result will be as follows:

As vacuum increases within the chamber 13 of the pump, the springs 26 and 27 will be compressed, the larger one 26 relatively much more freely than 27, the latter by virtue of the suction cup-like valve 30 which normally is being held closed by the same power causing compression of both springs. Now the relative expansion strength of these springs is such as to properly limit the reciprocal movement of the diaphragm 11 so that when it has traveled the proper predetermined distance towards the head 6 of the pump, the pressure upon the smaller spring 27 will be such as to force the valve 30 outwardly away from the port 29, thus admitting outside air into the chamber 13 and permitting the diaphragm 11 to return to its former position simultaneously with the return of the valve 30 to its original position against the wall 6 and again closing the port 29 ready for another cycle of operation by the vacuum of the engine.

The novel functioning of the resilient closure or rupture valve 30 is, that when sufficient pressure of the stem 28 has been developed to open it the least particle, it will instantly spring to its full open position and function most admirably as against any other type of valve thus far tried, they having failed utterly to so function.

It is apparent that as the diaphragm 11 is thus reciprocating, the chamber 14 of the pump will be alternately filled and emptied with air, the outside air entering said chamber through the check-valved port 17, before described, and the discharge taking place through the like-controlled port 18 into the expansion chamber 15 from where a continuous supply of such air is conducted into the water within the bait container.

It is to be noted that in the construction of the pump 5, the flange 31 of the stem 28 must be radially slotted or grooved as at 32, or the equivalent, to freely admit air radially thereabout when the plug is fully outwardly extended, as the only object for the stem is to provide an adequate support for the valve 30 in either of its extreme positions.

Having thus described my invention, what I claim and desire to secure by Letters Patent is:

1. In a vacuum operated pump having a casing, a reciprocable diaphragm dividing said casing into a power chamber and a pumping chamber, said pumping chamber having a valved air intake port and a valved air outlet port, means for operating said pump comprising means biasing said diaphragm to normal position where said pumping chamber is in reduced condition, a connection having an opening to said power chamber to which a vacuum source is attached to exhaust air from said power chamber whereby said diaphragm moves against said biasing means and air enters said pumping chamber through said air intake port and enlarges said pumping chamber, said power chamber having a second opening therethrough of greater size than first said opening, and a rupture valve for said second opening which is controlled by said diaphragm to open as the latter reaches a predetermined position and overcome said vacuum source whereby said biasing means forces said diaphragm back to normal position closing said rupture valve and forcing air out of said pumping chamber through said outlet port.

2. A pump for operation by a source of vacuum comprising, a casing, a reciprocable diaphragm within said casing and dividing same into a power chamber and a pumping chamber, said power chamber having an opening therethrough opposite said diaphragm, a valve installed over said opening to open and close same, means controlled by said diaphragm to open said valve, means biasing said diaphragm to normal position away from said opening, said power chamber having a second opening therethrough of smaller size than said first mentioned opening to which a source of vacuum is connected to create a vacuum and thereby close said valve and draw said diaphragm toward said first mentioned opening against said biasing means, said first mentioned means being adapted to open said valve as said diaphragm reaches a predetermined position and rupture the vacuum created in said power chamber by said vacuum source whereupon said diaphragm is returned to normal position by said biasing means, said pumping chamber having a valved port through which air enters as said diaphragm is moved by said vacuum source, and said pumping chamber having a valved outlet port through which air is forced as said diaphragm returns to normal position.

3. A pump for operation by a vacuum source comprising a walled casing, a reciprocable diaphragm within said casing and dividing same into a pumping chamber and a power chamber, said power chamber having an opening therethrough opposite said diaphragm, a vacuum rupture valve installed over said opening on the outer side of said casing for opening and closing said opening, a spring installed within power chamber between said diaphragm and said valve to bias the latter towards open position, a second spring installed between said diaphragm and the wall of said casing to bias said diaphragm away from said opening, said power chamber having an opening therethrough to which a source of vacuum is attached to draw said valve to closed position and cause said diaphragm to move against the bias of said second spring, said pumping chamber having an air intake port and an air exhaust port, said ports being check valved so that air enters said pumping chamber as said diaphragm moves toward said rupture valve and air is forced from said pumping chamber when said diaphragm moves in the opposite direction, and said first mentioned spring being adapted to open said rupture valve when said diaphragm reaches a predetermined position for overcoming said vacuum source permitting said second spring to return said diaphragm to normal position.
